UNITED STATES PATENT OFFICE.

EDWARD P. DONNELLAN, OF BROOKLYN, NEW YORK, ASSIGNOR TO STANDARD-JOHNSON CO., INC., OF BROOKLYN, NEW YORK, A CORPORATION OF NEW YORK.

COUNTING MECHANISM.

Application filed May 25, 1922. Serial No. 562,558.

To all whom it may concern:

Be it known that I, EDWARD P. DONNELLAN, a citizen of the United States, residing at Brooklyn, in the county of Kings and State of New York, have invented certain new and useful Improvements in Counting Mechanism; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15. This invention relates, generally, to improvements in counting machines for counting flat disc-like objects, such as coins, buttons, tokens, etc., in lots of predetermined number.

20. The invention has for its principal object to provide a novel tallying or counting mechanism for counting machines combined with automatic stop devices therefor, whereby the operation of the tallying mechanism is automatically interrupted and the machine stopped or locked against further operation after any desired predetermined number of coins or other articles have been counted.

25. Other objects of this invention, not at this time more particularly enumerated, will be clearly understood from the following detailed description of the same.

30. With the objects of the invention in view, the same consists, primarily, in the novel improved tallying mechanism for counting machines hereinafter set forth; and, furthermore, this invention consists in the novel arrangements and combinations of the various parts, as well as in the details of the construction thereof, all of which will be herein-after more fully described in the following specification, and then finally embodied in the claims which are appended thereto.

35. The invention is clearly illustrated in the accompanying drawings, in which:—

40. Figure 1 is a plan view of the novel combined tallying and automatic stop mechanism for counting machines, made according to and embodying the principles of this invention; Figure 2 is a part plan and part horizontal section through the same. wheel 6 which meshes with a spur gear 7 fixed upon said spindle 2. Said counter gear wheel 6 has a ratio of revolution to said spur gear 7 of one to ten, i. e., said spur gear, as actuated by said star-wheel or counter disc 3, makes ten revolutions to produce one revolution of said counter gear-wheel 6. Fixed upon said spindle 2 is a ratchet wheel 8, which is engaged by a 10 spring-pressed pawl 9, pivoted upon said base-plate 1, which serves to prevent rotation of said star-wheel or counter disc 3 in a backward direction, and consequently also prevents any backward movement of the 15 counter-gear wheel 6 which is actuated by said star-wheel or counter-disc.

Secured upon the upper face of said counter gear-wheel 6, by screws 10 or any other suitable fastening means, so that it 20 rotates with the counter gear-wheel 6, is a lock-ratchet wheel 11, of slightly smaller diameter than the diameter of said counter gear-wheel 6.

The reference character 12 indicates a 25 suitable casing or cover for enclosing the counter-gear mechanism above described, and which is also adapted to serve as a support for additional elements of the tallying mechanism. Fixed upon the upper 30 outer side of said casing or cover 12 is a scale-plate 13, provided in its upper side with an annular inverted T-shaped groove or channel 14. The outer marginal portions of the upper side of said scale-plate 13 35 is provided with a graduated scale 15, which divides the same into divisions, each division corresponding to the movement of the counting mechanism produced by the actuation thereof by a single article. In the 40 illustration of the invention as shown in the drawings, the scale is marked off to provide one hundred divisions, the mechanism being arranged so that actuation of the star-wheel or counter disc 3 by one hundred 45 articles will produce one complete revolution of the counter gear wheel 6.

Rotatably mounted upon the upper end of said journal stud 5 is a stop control disc 16, to the underside of which is fixed a latch 50 ratchet-wheel 17 of somewhat larger diameter than said stop-disc but smaller in diameter than said lock-ratchet wheel 11. Said stop control disc 16 with its latch ratchet-wheel 17 are registered or positioned 55 over said counter gear-wheel 6 and its lock ratchet-wheel 11, and are capable of being turned in a rearward or reverse direction independently of the latter, but are interlocked with said counter gear-wheel 6 and 60 its lock ratchet-wheel 11 so as to turn therewith in a forward direction when the same are operatively actuated. The means for so interlocking the said parts comprises a 65 spring pressed yieldable pawl or latch member 18, the casing or barrel 19 of which is

fixed upon the upper surface of said lock ratchet-wheel 11, so that said latch member 18 will operatively engage the teeth of said latch ratchet-wheel 17. The casing or cover 70 12 is provided with a central opening 20, and in like manner the annular scale-plate 13 provides a central opening alined with said casing opening 20. Said stop control disc 16 is provided on its upper side with a hub portion 21, which projects upwardly 75 through the openings in said casing and said scale-plate, and the same is provided at its upper extremity with a square shank 22 which projects above the upper surface of said scale-plate 13.

Fixed on said stop control disc 16, so as to surround its hub 21 and so as to be positioned in the opening of said scale-plate 13, flush therewith, is a filler block 23, which rotates with said stop-disc. 80 Adjustably mounted on said square shank 22 is a radially extending stop-plate 24. Said stop-plate 24 is provided in its body portion with a rectangular opening or slot 25 to receive said square shank 22, so that the stop-plate 24 is longitudinally movable 85 on said square shank to either a normal outwardly projected position (as shown by the full lines in Figure 1), or to a retracted position (as shown by the dotted lines in 90 said Figure 1). The means for holding the stop-plate 24 in either one or the other of its two positions, comprises a spring pressed latch-member 26, the casing or barrel 26' of 95 which is fixed upon the upper surface of said filler block 23, so that the latch-member is normally pressed toward one side of said stop-plate 24, said side being provided with an indented notch 27 engageable by said latch-member to hold the stop-plate 24 in 100 normal forwardly projected position, and a second indented notch 28 engageable by said latch-member to hold the stop-plate 24 in 105 its retracted position. Said stop-plate 24 is provided at its outer free end with a 110 stop-projection 29, which terminates in a pointer member 30 normally adapted to co-operate with the graduated scale 15 of the scale-plate 13. Adjustably movable in said 115 groove or channel 14 of said scale-plate 13 is a stop-post device, the same comprising a threaded shank 31 having a T-head 32 at its lower end disposed in said groove or channel 14, and threaded on said shank 31 is a lock-nut 33, which, when screwed down, 120 binds the T-head relative to said channel or groove 14 to thereby lock said stop-post device in any desired adjusted position. Secured to the hub 21 of said stop control disc 16, above said stop-plate 24, is a knob or 125 finger-piece 34.

Mounted on said base-plate 1, at one side of said counter gear-wheel 6 and associated parts as above described is a bracket 35 for supporting barrel 36 provided with a guide-way 37 open toward the counter gear-wheel 130

mechanism. Slidable in said guideway 37 is a lock-plunger 38, having at its lower outer free end lock-teeth 39, adapted at proper times to engage or intermesh with the teeth of said lock ratchet-wheel 11 to thereby prevent operative movement of the counter gear-wheel mechanism. The rear end of said lock-plunger 38 is provided with a stem 40 which extends outwardly through the rear end wall of said barrel 36, its outer end having a knob or finger-piece 41. The upper side of said lock-plunger 38 is provided with a groove 42 in which is engaged by the end of a stop screw 43 connected with said barrel 36, so that the longitudinal movement of said lock-plunger 38 is properly limited. A compression spring 44, arranged intermediate the rear end of said lock-plunger and the rear end wall of said barrel, exerts a normally outward thrusting pressure upon said lock-plunger. Connected with the upper forward end of said lock-plunger is a forwardly projecting control rod 45, the free end of which is provided with a nosing 46 which engages the periphery of said stop control disc 16. Said stop control disc 16 is provided in its periphery with an indented notch 47 which, at proper times, receives said nosing 46 of the control rod 45. Pivotaly mounted on said stop control disc 16 is a hold-out pawl 48, which is provided with a lip 49 extending downwardly over the periphery of said stop control disc 16. Said hold-out pawl 48 is normally actuated by a compression spring 50 to yieldably retain the same against a stop-pin 51, in which position the lip 49 closes over the notch 47 in the periphery of said stop control disc 16. The stem 40 of the lock-plunger 38 is provided with a cross-pin 52 in its external portion. Rotatably engaged on said stem 40 abutting the rearward end of said barrel 36 is a collar 53 provided in its outer face with a transverse groove 54 in which said cross-pin 52 is normally engaged or seated. In order to hold the lock-plunger 38 in an inoperative position, as is necessary when it is desired to operate the counting machine for continuous or uninterrupted counting, said stem 40 and the lock-plunger 38 is retracted and the collar 53 is turned to remove the groove 54 from the path of said cross-pin 52, so that the latter rests against the outer face of the collar 53, thus retaining said lock-plunger in retracted and inoperative relation to the counter gear-wheel mechanism.

Mounted on said base-plate 1 in a suitable location is a hand manipulatable pivoted stop dog 55 which may be turned to engage the teeth of the lock ratchet-wheel 11 to hold the counter gear-wheel mechanism inoperative, under circumstances subsequently to be described.

The operation of the above described counting mechanism is as follows:—

Assume that it is desired to count twenty-five articles, and have the counting mechanism automatically lock the machine against further delivery of articles upon the counting and passing out of the machine of the twenty-fifth article. The knob 34 is turned to position the pointer member 30 of the stop plate 24 upon the twenty-fifth division of the scale 15, and then the stop-post device is moved against the stop-projection 29 and locked relative to the groove or channel 14 of the scale plate 13 (the stop-plate 24 occupying its normal forwardly projecting position so as to properly engage said stop-post device). In turning the stop-plate 24 to the above-described position, the stop control disc 16 is turned back to remove the stop-notch 47 to a position distant from the control rod 45 equivalent to that requiring the actuating engagement of twenty-five articles with the counting mechanism to rotate the stop control disc in operative direction back to normal initial stopped engagement with the said control rod 45. In so turning back the stop control disc 16 the control rod nosing 46 rides out of the notch 47 on to the periphery of the stop control disc, thereby thrusting back the control rod 45, and in turn retracting the lock-plunger 38 to remove the lock-teeth 39 thereof from locking engagement with the teeth of the lock ratchet-wheel 11, thus freeing the counter gear-wheel 6 for forward movement, and consequently releasing the entire counting mechanism and coin delivery mechanism of the machine for operative movement. If the counting machine is hand driven, the operator now actuates the same thereby causing the articles to be counted to be successively delivered in passing and actuating engagement with the star-wheel or counter-disc 3, thus rotating the same, and thereby transmitting through the spur gear 7, a forward rotative movement to the counter gear-wheel 6. As the counter gear-wheel 6 rotates, the stop control disc 16 and associated parts turn with it, since the pawl 18 interlocks with the latch ratchet-wheel 17 to cause the stop control disc 16 and counter gear-wheel to move together in operative direction, thus returning the notch 47 back toward the control rod 45. As the twenty-fifth article passes the star-wheel or counter-disk 3, the stop control disc 16 has moved its notch 47 into line with the nosing 46 of the control rod 45, so that the spring 44 exerting its pressure upon the lock-plunger 38 thrusts the latter forward, such movement being permitted by the entrance of the control rod nosing 46 into said notch 47. This forward movement of the lock-plunger carries the teeth

39 thereof into operative meshing engagement with the teeth of the lock ratchet-wheel 11, thereby locking the counter gear-wheel against further forward rotation, and 5 consequently holding the star-wheel or counter disc 3 against further operative movement, so that the machine is locked against further delivery and counting of articles, after completing the count of the desired 10 twenty-five articles. Now, if it is desired to continue counting the articles in lots of twenty-five, the operator turns back the stop control disc 16 until the stop projection 29 engages the stop-post device, whereupon the 15 machine is set to repeat the above described operations. This may be done as often as desired.

It will be understood that if it is desired to count the articles in lots of any desired 20 odd or even number, the stop-plate 24 is initially turned back to the number on the scale 15 corresponding to the number of articles making up the desired lot, and then the stop-device is set to correspond to the 25 initially set position of the stop-plate thus determined, whereupon the machine may be operated repeatedly in the manner above described.

In the event the machine is of the motor 30 driven type, so that the mechanism delivering the articles past the star-wheel or counter-disc 3 runs continuously, it is necessary, after the completion of the counting of the desired lot of articles, to throw the 35 stop-dog 55 into holding engagement with the teeth of the lock ratchet-wheel 11, to thereby hold the counter gear-wheel 6 against operative movement while the lock-plunger 38 is released therefrom during the 40 resetting of the stop control disc 16. After the stop control disc is reset, the stop-dog is released, so that the machine and counting mechanism immediately begins to function.

When it is desired to count out the articles 45 in lots of one-hundred, the maximum lot number arranged for in the illustrated form of the mechanism, the stop-plate 24 is retracted to the dotted position shown in Figure 1, in which position the stop projection 29 and pointer member 30 is withdrawn so as to clear or pass the stop-device of the scale-plate 13. To begin operations, the knob 41 is utilized to retract the lock-plunger 38, thus releasing the lock-teeth 39 50 thereof from holding engagement with the teeth of the lock ratchet-wheel 11, while at the same time withdrawing the nosing 46 of the control rod 45 from the notch 47 of the stop control disc 16. When the nosing 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 9835 9840 9845 9850 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999

leased for operation. The operator now actuates the machine to deliver the articles successively into actuating engagement with the star-wheel or counter disc 3, so that the counter gear-wheel 6 and the stop control disc 16 are rotated in a forward direction. The rotation of the stop control disc 16 carries the lip 49 of the hold-out pawl 48 away from the nosing 46 of the control rod 45 permitting the latter to engage the periphery of the stop control disc 16 beyond the notch 47. Since the counting of one-hundred articles will produce one complete revolution of the counter gear-wheel and stop control disc, the notch 47 is again registered opposite the nosing 46, so that the latter may enter therein, whereupon the lock-plunger again moves into locking relation to the lock ratchet-wheel 11. As the notch 47 is approaching the nosing 46, the latter engages the edge of the lip 49 of the hold-out pawl 48, pressing the same back against the tension of the spring 50, and thereby exposes the notch 47 to the entrance of the nosing 46 therein. The above operations may be repeated to produce successive counts of articles in lots of one hundred.

If it is desired to set the machine for continuous counting, the lock-plunger 38 is retracted to released position, which withdraws the cross-pin 52 from the groove 54 of the collar 53, and the latter is given a quarter turn to dislocate the groove relative to the cross-pin, so that when the lock-plunger 38 is released, the cross-pin will engage the outer face of the collar 53, the lock-plunger being thereby impeded from returning to locking position and consequently freeing the counter gear-wheel mechanism for continuous operation. Under these circumstances the stop-plate 24 is withdrawn to retracted position so as to clear the stop-post device of the scale-plate 13.

It will be understood that a total count of all articles passed through the machine may be recorded by gearing to said spindle 2, or other convenient portion of the counting mechanism, a total-adder device (not shown).

I am aware that some changes may be made in the general arrangements and combinations of the various devices and parts as well as in the details of the construction thereof, without departing from the scope of the present invention as set forth in the foregoing specification, and as defined in the appended claims. Hence, I do not limit my invention to the exact arrangements and combinations of the several devices and parts as described in the said specification, nor do I confine myself to

the exact details of the construction of said parts as illustrated in the accompanying drawings.

I claim:—

for operating said counter gear-wheel, a lock ratchet-wheel fixed upon said counter gear-wheel, a spring actuated lock-plunger having lock-teeth operatively engageable with 5 the teeth of said lock ratchet-wheel to lock said counter gear-wheel against operation, a control rod projecting forwardly from the end of said lock-plunger, a rotary stop control disc having a notch in its periphery engageable by the end of said control rod, means for coupling said stop control disc for rotation with said counter gear-wheel yet permitting independent reverse rotation thereof for initial setting, and means for 10 retaining said lock-plunger and its control rod in retracted inoperative position.

8. In mechanism of the kind described, a counter gear-wheel, a driving spindle in geared relation to said counter gear-wheel, 20 a star-wheel on said driving spindle to receive the actuating engagement of articles to be counted, a lock ratchet-wheel in fixed relation to said counter gear-wheel, a spring actuated lock-plunger having lock-teeth 25 operatively engageable with said lock ratchet-wheel, a control rod projecting from the forward end of said lock-plunger, a rotary control disc, a latch ratchet-wheel in fixed relation to said control disc, a spring 30 actuated pawl device in fixed relation to said lock ratchet-wheel and said counter gear-wheel to operatively engage the teeth of said latch ratchet-wheel, and said control disc having a notched seat in its periphery accessible to the entrance therein of the 35 free end of said control rod to permit operative movement of said lock-plunger.

9. In mechanism of the kind described, a counter gear-wheel, a driving spindle in 40 geared relation to said counter gear-wheel, a star-wheel on said driving spindle to receive the actuating engagement of articles to be counted, a lock ratchet-wheel in fixed relation to said counter gear-wheel, a spring 45 actuated lock-plunger having lock-teeth operatively engageable with said lock ratchet-wheel, a control rod projecting from the forward end of said lock-plunger, a rotary control disc, a latch ratchet-wheel in 50 fixed relation to said control disc, a spring actuated pawl device in fixed relation to said lock ratchet-wheel and said counter gear-wheel to operatively engage the teeth of said latch ratchet-wheel, said control disc 55 having a notched seat in its periphery accessible to the entrance therein of the free end of said control rod to permit operative movement of said lock-plunger, a scale-plate, and an indicator means carried by said control disc to cooperate with said scale-plate. 60

10. In mechanism of the kind described, a counter gear-wheel, a driving spindle in geared relation to said counter gear-wheel, a star-wheel on said driving spindle to receive the actuating engagement of articles 65

to be counted, a lock-ratchet-wheel in fixed relation to said counter gear-wheel, a spring actuated lock-plunger having lock-teeth operatively engageable with said lock ratchet-wheel, a control rod projecting from the forward end of said lock-plunger, a rotary contact disc, a latch ratchet-wheel in fixed relation to said control disc, a spring actuated pawl device in fixed relation to said lock ratchet-wheel and said counter gear-wheel to operatively engage the teeth of said latch ratchet-wheel, said control disc having a notched seat in its periphery accessible to the entrance therein of the free end of said control rod to permit operative movement of said lock-plunger, a scale-plate, an adjustable stop-post device mounted on said scale-plate, and an indicator means carried by said control disc to cooperate with said scale-plate. 70 75 80 85

11. In mechanism of the kind described, a counter gear-wheel, a driving spindle in geared relation to said counter gear-wheel, a star-wheel on said driving spindle to receive the actuating engagement of articles 90 to be counted, a lock ratchet-wheel in fixed relation to said counter gear-wheel, a spring actuated lock-plunger having lock-teeth operatively engageable with said lock ratchet-wheel, a control rod projecting from the forward end of said lock-plunger, a rotary control disc, a latch ratchet-wheel in fixed relation to said control disc, a spring actuated pawl device in fixed relation to 95 said lock ratchet-wheel and said counter gear-wheel to operatively engage the teeth of said latch ratchet-wheel, said control disc having a notched seat in its periphery accessible to the entrance therein of the free end of said control rod to permit operative movement of said lock-plunger, a scale-plate, and an indicator means carried by said control disc to cooperate with said scale-plate, and means for retaining said lock-plunger 100 and its control rod in retracted inoperative position. 105 110 115

12. In mechanism of the kind described, a counter gear-wheel, a driving spindle in geared relation to said counter gear-wheel, a star-wheel on said driving spindle to receive the actuating engagement of articles to be counted, a lock ratchet-wheel in fixed relation to said counter gear-wheel, a spring actuated lock-plunger having lock-teeth operatively engageable with said lock ratchet-wheel, a control rod projecting from the forward end of said lock-plunger, a rotary control disc, a latch ratchet-wheel in fixed relation to said control disc, a spring actuated pawl device in fixed relation 120 to said lock ratchet-wheel and said counter gear-wheel to operatively engage the teeth of said latch ratchet-wheel, said control disc having a notched seat in its periphery accessible to the entrance therein of the free end of said control rod to permit operative movement of said lock-plunger, a scale-plate, and an indicator means carried by said control disc to cooperate with said scale-plate. 125 130

of the free end of said control rod to permit operative movement of said lock-plunger, and means for retaining said lock-plunger and its control rod in retracted inoperative 5 position.

13. In mechanism of the kind described, a counter gear-wheel, a driving spindle in geared relation to said counter gear-wheel, a star-wheel on said driving spindle to receive 10 the actuating engagement of articles to be counted, a lock ratchet-wheel in fixed relation to said counter gear-wheel, a spring actuated lock-plunger having lock-teeth operatively engageable with said lock ratchet-wheel, a control rod projecting from the forward end of said lock-plunger, a rotary 15 control disc, a latch ratchet-wheel in fixed relation to said control disc, a spring actuated pawl device in fixed relation to said lock ratchet-wheel and said counter gear-wheel to operatively engage the teeth of said latch ratchet-wheel, said control disc having a notched seat in its periphery accessible to the entrance therein of the free end of said control rod to permit 20 operative movement of said lock-plunger, an auxiliary manipulatable lock dog to hold said counter gear-wheel inoperative independently of said lock-plunger.

14. In mechanism of the kind described, a counter gear-wheel, a driving spindle in geared relation to said counter gear-wheel, a star-wheel on said driving spindle to receive 25 the actuating engagement of articles to be counted, a lock ratchet-wheel in fixed relation to said counter gear-wheel, a spring actuated lock-plunger having lock-teeth operatively engageable with said lock-ratchet-wheel, a control rod projecting from the forward end of said lock-plunger, a rotary 30 control disc, a latch ratchet-wheel in fixed relation to said control disc, a spring actuated pawl device in fixed relation to said lock ratchet-wheel and said counter gear-wheel to operatively engage the teeth of said latch ratchet-wheel, said control disc having a notched seat in its periphery accessible to the entrance therein of the free end 35 of said control rod to permit operative movement of said lock-plunger, a scale-plate, an adjustable stop-post device mounted on said scale-plate, an indicator stop-plate radially disposed and adjustably mounted relative to said control disc, means for holding said indicator stop-plate in either operative or inoperative position, and means for retaining said lock-plunger and its control rod in retracted inoperative position.

notched seat in its periphery accessible to the entrance therein of the free end of said control rod to permit operative movement of said lock-plunger, a scale-plate, an adjustable stop-post device mounted on said scale-plate, an indicator stop-plate radially disposed and adjustably mounted relative to said control disc, and means for holding said indicator stop-plate in either operative 50 or inoperative position.

15. In mechanism of the kind described, a counter gear-wheel, a driving spindle in geared relation to said counter gear-wheel, a star-wheel on said driving spindle to receive 55 the actuating engagement of articles to be counted, a lock ratchet-wheel in fixed relation to said counter gear-wheel, a spring actuated lock-plunger having lock-teeth operatively engageable with said lock ratchet-wheel, a control rod projecting from the forward end of said lock-plunger, a rotary 60 control disc, a latch ratchet-wheel in fixed relation to said control disc, a spring actuated pawl device in fixed relation to said lock ratchet-wheel and said counter gear-wheel to operatively engage the teeth of said latch ratchet-wheel, said control disc having a notched seat in its periphery accessible to the entrance therein of the free end 65 of said control rod to permit operative movement of said lock-plunger, a scale-plate, an adjustable stop-post device mounted on said scale-plate, an indicator stop-plate radially disposed and adjustably mounted relative to said control disc, means for holding said indicator stop-plate in either operative or inoperative position, and means for retaining said lock-plunger and its control rod in retracted inoperative position.

In testimony that I claim the invention set forth above I have hereunto set my hand this 22nd day of May, 1922.

EDWARD P. DONNELLAN.
